CLAIM

The ornamental design for an annular blade assembly for a rotary knife, as shown and described.

DESCRIPTION

FIG. 1 is a top perspective view of an annular blade assembly for a rotary knife in accordance with a first embodiment;

FIG. 2 is a top perspective view of the annular blade independent from the exemplary rotary knife;

FIG. 3 is a bottom perspective view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a side elevation view thereof; and

FIG. 9 is a cross-sectional view thereof along lines 9-9 in FIG. 4.

FIG. 10 is a top perspective view of an annular blade assembly for a rotary knife in accordance with a second embodiment;

FIG. 11 is a top perspective view of the annular blade independent from the exemplary rotary knife;

FIG. 12 is a bottom perspective view thereof;

FIG. 13 is a top plan view thereof;

FIG. 14 is a bottom plan view thereof;

FIG. 15 is a front elevation view thereof;

FIG. 16 is a rear elevation view thereof;

FIG. 17 is a side elevation view thereof; and

FIG. 18 is a cross-sectional view thereof along lines 18-18 in FIG. 13.

FIG. 19 is a top perspective view of an annular blade assembly for a rotary knife in accordance with a third embodiment;

FIG. 20 is a top perspective view of the annular blade independent from the exemplary rotary knife;

FIG. 21 is a bottom perspective view thereof;

FIG. 22 is a top plan view thereof;

FIG. 23 is a bottom plan view thereof;

FIG. 24 is a front elevation view thereof;

FIG. 25 is a rear elevation view thereof;

FIG. 26 is a side elevation view thereof; and,

FIG. 27 is a cross-sectional view thereof along lines 27-27 in FIG. 22.

The dashed lines shown are for environmental purposes only and form no part of the claimed design. The dashed-dot-dot lines designate boundaries and form no part of the claimed design.
